UNITED STATES PATENT OFFICE.

SAMUEL A. SNELL, OF ST. LOUIS, MISSOURI, ASSIGNOR TO MOON BROTHERS MANUFACTURING COMPANY, OF ST. LOUIS, MISSOURI, A CORPORATION OF MISSOURI.

JACK.

Application filed December 24, 1921. Serial No. 524,614.

To all whom it may concern:

Be it known that I, SAMUEL A. SNELL, a subject of the King of Great Britain, residing at the city of St. Louis and State 5 of Missouri, have invented a certain new and useful Improvement in Jacks, of which the following is a full, clear, and exact description, such as will enable others skilled in the art to which it appertains to 10 make and use the same, reference being had to the accompanying drawings, forming part of this application.

My invention relates to jacks and comprises an improved base, column, operating 15 mechanism, and housing for same.

One object of my invention is to produce an economical efficient framing by utilizing pressed metal parts which are adapted to be assembled with each other with minimum 20 labor to produce a rigid completed structure.

Another object of my invention is to provide a mechanism which will be positive in action, either in raising or lowering.

25 An additional object of my invention is to permit quick movement of the jack bar up to a load and down from a load although requiring a tooth by tooth movement when loaded whether being raised or lowered.

30 In the accompanying drawings, which illustrate a selected embodiment of my invention,—

Figure 1 is a side elevation of my improved jack.

35 Figure 2 is an enlarged detail showing a portion of the upright column, operating mechanism housing and operating handle in vertical section, and showing the saddle rack and operating mechanism in side elevation.

Figure 3 is a fragmentary detail similar to Figure 2, but showing the mechanism in a different operating position.

40 Figure 4 is a front elevation of the finger by which the jack is set to raise or lower.

Figure 5 is a front elevation of the column and mechanism housing.

Figure 6 is a top view of the same.

Figure 7 is a horizontal section on line 45 7—7 of Figure 1.

Figure 8 is an isometric view of the column.

Figure 9 is a transverse vertical section on line 9—9 of Figure 1 and showing a 50 modified assembly of the base and column.

Figure 10 is a bottom view of the base of the jack.

Figure 11 is an end view of the column before completion.

The base 1 is a dish-shaped metal stamping, the perimeter of which is flanged downward at 2 and the central portion of which is flanged upward at 3 and provided with angular notches 4 arranged as shown in Figure 10. Stiffening ribs 6 extend diagonally from each corner of the base to the adjacent corner of the rib 3. The vertical column 7 is preferably made from a flat plate bent into a hollow rectangular shape, as indicated in Figure 9, and has its meeting edges 10 welded to each other. The outside dimensions of column 9 equal the inside dimensions across the notches 5 in base 1. The column preferably has vertically extending notches 11 corresponding to the lateral projections on the base between notches 4 of the latter. This construction enables the column to be set into the base with the inter-notch portions of the base supporting the column and with the corner projections of the column laterally engaging notches 4 of the base, extending downwardly therefrom and there riveted over the bottom of the base.

In the modified assembly shown in Figure 9, a rectangular opening is formed in base 1, producing a blank 12 which I utilize to brace the lower end of the column by trimming the blank so that its outside dimensions correspond to the inside dimensions of the column. This blank is then inserted in the end of the column, and the base, column and blank are then welded together, the blank providing the necessary metal to back the relatively thin section present in the column at the welding point.

Near the upper end of the column, one side is slotted at 13 for the reception of operating pawls, as shown in Figures 2 and 3.

The operating mechanism housing is preferably formed of a flat plate bent into a deep U-section which tightly embraces column 7 on three sides and extends outwardly from the fourth side of the latter a substantial distance. The vertical side walls of housing 15 are braced by plates 16 and 17 which may be riveted to the housing by integral rivets 18 formed on the latter. Due to the tight gripping of the column by the housing, a single fastening means connect-

ing these two members is all that is required to maintain their assembly. Figure 1 indicates a screw 19 and a spot weld 20 as the securing means, but it is to be understood that only one of these means is necessary. If screw 19 alone is used the column and housing may be disassembled, while the spot weld 20 provides a permanent assembly.

10 A handle lever 21 is preferably of rectangular section similar to column 7, but the lower end of same resembles a U-shape which faces upwardly and receives operating pawls 22 and 23 which engage the teeth of the saddle rack 20. Pawls 22 and 23 are pivoted on the lever by means of pins 24 and 25, respectively. Pin 24 extends through pawl 22, the sides of handle 21 and the sides of housing 15, being headed at one end and provided with a cotter 26 at the opposite end. Pin 25 extends through pawl 23 and the sides of handle 21, its ends abutting against the sides of housing 15. When the operating handle 21 is raised and lowered, a pin 27 extending transversely through the 25 handle engages the edges of the side walls of housing 15 adjacent to the open side of the latter. This engagement positively limits the movements of the handle, relieving the pawls and other parts of the housing 30 from the possibility of being forced into abnormal position or unduly strained by the leverage exerted at the forward end of the handle.

35 Mounted on the front of column 7 is a bracket 28 which forms a seat and housing for a coil spring 29, the upper end of which yieldingly supports a plunger 30. Plunger 30 is connected to an eccentric finger 31 below bracket 28 which is adapted to be moved from the dotted line position shown in Figure 4 to the full line position there indicated to withdraw the plunger from the projected position shown in Figures 2 and 3. Pawls 22 and 23 are provided with downwardly extending lugs 32 and 33 terminating just above plunger 30. When the plunger is released, as shown in Figures 2 and 3, it pushes upwardly against one or the other or both of these lugs according to the position of 40 the operating handle and the operation of the jack is as will be explained later. Pawls 22 and 23 are provided with individual springs 34 and 35, respectively, each of 45 which pushes its respective pawl inwardly toward a ratchet bar 36 of the usual construction. These springs are not strong enough to function as described, when plunger 30 is released and spring 29 is pressing the same upwardly, as shown in Figures 2 and 50 3.

55 When the eccentric finger 31 is in the full line position shown in Figure 4, and plunger 30 is fully withdrawn from possible contact with the lugs on the plugs, the jack 60 may be operated to lift a load in the usual

manner. Each downward movement of the handle will raise the ratchet bar by means of pawl 23 and pawl 22 will hold the bar in raised position to permit the handle to be raised and pawl 23 to be lowered to engage a lower tooth on the ratchet. Each of the pawls in this operation are thrust into engagement with the bar by their respective springs and each rides freely over the ratchet teeth as long as the bar moves upwardly.

70 When it is desired to lower the jack with its superimposed load, eccentric 31 is turned to the position shown in Figure 5. With the operating handle in the position shown in Figure 2, plunger 30 engages the lug 33 on pawl 23, thrusting the pawl out of engagement with the ratchet against the opposing tendency of spring 35. As the handle is lowered, pawl 23 and plunger 30 rise and plunger 30 engages projection 32 on pawl 22. Due to the fact that the load is supported at this time by pawl 22, the pawl will be held immovable and the upward movement of plunger 30 will be halted. Pawl 23, however, continues to rise and being released from plunger 30 will engage rack 36 and lift same enough to free pawl 22 which immediately moves out of engagement with the rack impelled thereto by plunger 30. Upward movement of the handle will now lower pawl 23 and the load supported thereby and as lug 33 on pawl 23 descends, it will engage plunger 30 forcing the same downwardly, thereby disengaging lug 32 on pawl 22 and permitting the latter impelled by spring 34 to move back into engagement with ratchet bar 36.

75 This operation may be continued until the jack is released from its load. When this happens, upon further movement of the handle, plunger 30 will engage both lugs and throw out both pawls, as shown in Figure 3. It will be understood that spring 29 is strong enough to overcome not only the combined action of springs 34 and 35, but also the friction on the point of pawl 22 due to the net weight of ratchet bar 36. This disengagement of the ratchet bar by both pawls enables the bar to drop to its lowest position, but eliminates tooth by tooth lowering of the bar as is usually necessary in ratchet jacks. Pawls 22 and 23, bracket 28, plunger 30, and finger 31 are stamped from sheet metal and as my jack is formed throughout almost entirely of metal pressings, it is very light for its capacity without any sacrifice of rigidity and strength.

80 100 105 110 115 120 125 130 The construction shown eliminates a number of small parts and manufacturing operations and results, in large production, in substantial economies.

I contemplate the usual modifications in the commercial development of my invention, without departing from the spirit thereof as expressed in the appended claims.

I claim:

1. In a jack, a base provided with angular slots of restricted area in its upper face, and a tubular column, the lower end of which is provided with vertical notches seated on the metal between the base slots, the projections between the column notches being angular and extending into the base slots.
- 10 2. In a jack, a base comprising a metal pressing in the shape of a rectangular inverted dish having centrally positioned angular openings adapted to receive and retain a rectangular column and provided with a stiffening flange surrounding the angular openings, and diagonal bosses extending from each corner thereof to each corner of the base.
- 20 3. In a jack, a vertical body member comprising a metal plate bent to form a hollow rectangular column, a rectangular housing for the jack operating mechanism comprising a metal plate surrounding said column and gripping three sides thereof extending laterally from the fourth side and there braced transversely at top and bottom, and an operating handle fulcrumed between the sides of said housing and extending outward from the fourth side of said column through said housing.
- 30 4. In a jack, a pressed metal base having an opening in its upper face, a pressed metal column seated in said base and extending into said opening, a ratchet bar slidable therein, a pressed metal housing surrounding said column and closely fitting three sides thereof, a single fastening element securing said housing in place on said column, and mechanism mounted in said housing and extending through the side of said column to operatively engage said rack.
- 40 5. In a jack, an upright body member, a ratchet bar slidable therein, an open-sided

housing secured to said member and extending laterally from one side thereof, a handle inserted through the open side of said housing, a ratchet bar opening mechanism mounted on said handle and a removable pin pivotally assembling said handle and the mechanism carried thereby with said housing, said handle and mechanism being removable as a unit through the open side of said housing.

45 6. In a jack, a rectangular housing, a U-shaped handle extending therein with its sides bearing against the sides of the housing, an operating pawl inserted in said handle, a fulcrum pin extending through said pawl, handle and housing and removably secured to the latter, a second pawl inserted in said handle, a pivot pin extending through said second pawl and said handle and retained therein by the sides of said housing, said handle, pawls and pivot pin being removable as a unit through said housing.

55 7. In a jack, a standard comprising a column and a mechanism housing extending outwardly therefrom and having an opening on the side farthest from said column, an operating lever extending into said housing through said opening, and projections on the side of said lever adapted to engage the edges of the housing walls adjacent to its open side to limit the movement of the lever.

60 8. In a jack, a pair of channel-shaped pivoted pawls having their channels facing each other forming an enclosure, and a pawl operating spring mounted on the pawl pivots and wholly positioned between the channel like walls of said pawls.

65 In testimony whereof I hereunto affix my signature this 19th day of December, 1921.

SAMUEL A. SNELL.
